UNITED STATES PATENT OFFICE.

FRANK BICK, OF AMSTERDAM, OHIO.

DESIGN FOR A STAND.

51,037.

Specification for Design. Patented July 17, 1917.

Application filed May 21, 1917. Serial No. 170,074. Term of patent 7 years.

To all whom it may concern:

Be it known that I, FRANK BICK, a subject of the Emperor of Austria, residing at Amsterdam, in the county of Jefferson and State of Ohio, have invented a new, original, and ornamental Design for a Stand, of which the following is a specification, reference being had to the accompanying drawing, forming part thereof.

The figure is a view in perspective of a stand, showing my new design.

I claim:—

The ornamental design for a stand, as shown.

FRANK BICK.
